UNITED STATES PATENT OFFICE.

HENRY P. GROSS, OF BALTIMORE, MARYLAND; ROBERT BIGGS ADMINISTRATOR OF
SAID GROSS, DECEASED.

BASKET.

1,157,528.

Specification of Letters Patent.

Patented Oct. 19, 1915.

Application filed October 3, 1914. Serial No. 864,939.

To all whom it may concern:

Be it known that I, HENRY P. GROSS, a citizen of the United States, residing at Baltimore, in the State of Maryland, have 5 invented a new and useful Basket, of which the following is a specification.

This invention has reference to baskets, and its object is to provide a strengthening member for handled baskets whereby the handle is so effectively anchored to the body of the basket and is so strengthened and reinforced as to maintain its hold in the body of the basket under circumstances which would ordinarily rend the handle therefrom.

10 In accordance with the present invention the handle may be of the usual hoop or bail form, while the body of the basket is of woven form into which the ends of the handle core are usually inserted at opposite 15 sides of the body of the basket. Bound on to the handle core there is a metal member which may be made of two wire strands twisted together through the mid portion of their length, the twisted part being about 20 equal in length to the exposed portion of the handle between the sides of the basket. The two wires for the remaining portion of their length toward their ends are free or 25 separate, and are individually twisted about 30 the top and bottom rails of the basket body and are then carried along the bottom of the basket either to a common central rail or to other rails within the bottom portion of the basket, so that the wire strands are not 35 only connected to the top and bottom rails of the sides of the basket, but underride the basket, thereby anchoring the sides from spreading at the bottom portion, and to a 40 commensurate extent strengthening the whole structure.

The invention will be best understood from a consideration of the following detailed description, taken in connection with the accompanying drawings forming a part 45 of this specification, with the further understanding that while the drawings show a practical form of the invention, the latter is not confined to any strict conformity with the showing of the drawings but may be 50 changed and modified so long as such changes and modifications mark no material departure from the salient features of the invention.

In the drawings:—Figure 1 is a perspective skeleton view of a basket showing the

handle with its usual wrapping complete in part, and also showing the wire reinforcement member and the scheme of connection with the various rails of the body of the basket. Fig. 2 is a perspective view of the wire reinforcement member before application to the basket body. Fig. 3 is a plan view, more or less schematically displayed, showing the manner of connecting the extremities of the reinforcement member to a single mid rail in the bottom of the basket. Fig. 4 is a perspective view of a completed basket indicating the reinforcement in dotted lines. Fig. 5 is a view similar to Fig. 3 showing a somewhat different mode of connecting the extremities of the wire reinforcement to the bottom of the basket.

Referring to the drawings, and first to Fig. 4, there is shown a basket 1 of common form which is usually woven of willow strips, although the present invention is not confined to an ordinary woven willow basket. In Fig. 1 the skeleton frame only of the basket is shown, and in the figure top side rails 2 and bottom side rails 3 are displayed, while there is also shown an intermediate longitudinal bottom rail 4 midway between the side rails, and in the complete basket these parts are all properly united, and the willow strips are interwoven so as 85 to inclose them.

There is provided a handle 5 ordinarily made of a core 6 of suitable size having the ends inserted in the sides of the body of the basket and extending practically to the bottom rails 3. It is customary to wind the core 6 with a band 7 of willow or other suitable material both for ornament and protection of the hand of the person carrying the basket. This band 7 in the ordinary 90 type of baskets is anchored in the sides of the basket, and so aids in sustaining the load carried in the basket.

In accordance with the present invention there is provided a reinforcement made up of two strands 8 of wire of suitable gage twisted together as shown at 9 through an appropriate length of the middle portion of the two strands, this twisted length being about that of the length of the handle 5 between the side rails 2. The twisted portion 9 is applied to the upper or outer surface of the core 6, and is there held by the wrapping 7. Each strand 8 on both sides of the twisted portion 9 is given a turn about the 105 110

corresponding rail 2 on opposite sides of the core 6 where passing the rail, this turn being indicated at 10. The strands 8 are then carried through the corresponding sides of the basket adjacent to that portion of the core 6 lodged within the corresponding sides of the basket until the bottom rail 3 is reached and both strands 8 are twisted about the bottom rail 3, as indicated at 11. From 10 thence both strands are carried along the bottom of the basket toward the middle rail 4 and their extremities are twisted thereabout, as indicated at 12, the strands of wire approaching the rail 4 from respectively 15 opposite sides.

Instead of a mid rail 4, two intermediate bottom rails 13, 14 may be provided, these rails being relatively close together and spaced from the side rails 3. In this case 20 one of the extremities of the pair of wires or strands 8 is twisted about the rail 13, as indicated at 15, while the corresponding other extremities of the wire strands 8 are twisted about the rail 14, as indicated at 16. 25 When the extremities of the strands 8 are carried through the bottom of the basket and are both joined to the single rail 4 all strain upon these strands tending to pull them away from the middle of the basket is resisted by the opposite pulls of the respective opposite ends of the strands where encircling the one rail 4. Where two intermediate rails 13, 14 are provided the mutual action is not directly upon one rail, but 30 is exerted through the intermediate woven portions of the bottom of the basket.

In the finished basket the wire strands are invisible, being hidden by the wrapping 7 and by the woven material constituting the 40 walls of the body portion of the basket. Such a basket may be loaded to the capacity of the strength of the body portion without danger to the handle, for the wire strands 8 form a strong reinforcement without the 45 strands being of unduly heavy gage, and the walls and rails of the basket are well sustained by these strands. Even the bottom of the basket is held against undue sagging by the strands since their tendency is to pull 50 oppositely across the bottom of the basket and so sustain the load directly by the handle, which load would otherwise have to be sustained by the bottom and sides of the basket up to the handle.

55 While the invention is shown as applied to a generally rectangular basket, it will be understood that it may be applied to any shape of basket whether rectangular or oval or round or otherwise formed.

60 The wire strands where extending from top to bottom of the side walls of the basket on opposite sides of that portion of the core 6 of the handle entering the sides of the basket may diverge, as indicated in the 65 drawings, so as to support the bottom rail 3

on each side of the basket at considerably spaced points and from thence the strands may converge as indicated as they approach the middle rail 4 or the intermediate rails 13 and 14. It will be understood, of course, 70 that the gage of wire employed will vary in accordance with the size of the basket and the load for which it is intended.

What is claimed is:—

1. A basket having sides and a bottom 75 and also having a handle, and a reinforcement comprising wires attached to the handle with their ends extended through the side walls of the basket on opposite sides of the handle where entering the side walls 80 and from thence directed across the bottom of the basket toward the center thereof and permanently secured to the bottom of the basket at the extremities.

2. A basket provided with a handle and 85 rails at the top and bottom of the sides and also intermediately of the bottom, and a reinforcement comprising wires attached to the handle with their ends extended through the side walls of the basket on opposite sides of the handle where entering the side walls and from thence directed 90 across the bottom of the basket toward the center thereof and secured to the bottom of the basket at the extremities, the wires being 95 twisted about the rails where meeting them.

3. A basket having sides and a bottom and also having a handle, and a reinforcement member comprising strands of wire twisted 100 together throughout a portion of their length with the twisted portion overriding the handle of the basket and secured thereto and the remaining portions of the wire strands carried through the side portions of the basket 105 on opposite sides of the handle and thence along the bottom of the basket with the extremities of the wires permanently secured to said bottom of the basket.

4. A basket provided with a handle and 110 with a body having top and bottom rails, and a reinforcement member comprising strands of wire twisted together throughout a portion of their length with the twisted portion overriding and secured to the handle and with the ends of the wires twisted 115 about the top and bottom rails of the basket adjacent to the handle and carried toward the center portion of the bottom of the basket and there permanently secured to said bottom.

5. A basket provided with a handle and top and bottom side rails and an intermediate bottom rail, and a reinforcement member 125 comprising strands of wire twisted together throughout the intermediate portion of their length with the twisted portion secured to the handle in overriding relation thereto and having the ends beyond the twisted portion each twisted about a corre- 130

sponding top and bottom side rail and thence carried to the intermediate bottom rail and having its extremity twisted thereabout.

- 5 6. A basket provided with a handle and top and bottom side rails and an intermediate bottom rail, and a reinforcement member comprising strands of wire twisted together throughout the intermediate portion 10 of their length with the twisted portion secured to the handle in overriding relation thereto and having the ends beyond the twisted portion each twisted about a corre-

sponding top and bottom side rail and thence carried to the intermediate bottom 15 rail and having its extremity twisted thereabout, the wire strands diverging on opposite sides of the handle from the top side rail to the bottom side rail.

In testimony that I claim the foregoing 20 as my own I have hereto affixed my signature in the presence of two witnesses.

HENRY P. GROSS.
